PILE LOOM CONSTRUCTION

John Lowrie, Thompsonville, Conn.

Application May 6, 1935, Serial No. 19,967

5 Claims. (Cl. 139—47)

This invention relates to improvements in that type of loom construction used for making pile fabrics such as pile carpets.

Loom structure for this purpose is generally well known. My improvements are directed to the means and mode of operation for making the loops in the pile threads, in cutting the loops to form the pile, and in arranging these means for more efficient and convenient operation. An additional feature of improvement is in the devices I provide for convenient adjustment of the parts to different sizes of loops and different arrangements of pile warp thread manipulation.

I will disclose only such parts of the loom as may be needed to make my improvements clear to one skilled in the art. The way in which my improved means are mounted in the loom structure and related to the weaving operation is shown in the accompanying drawings.

Fig. 1 is a detail view with parts in section, of enough loom mechanism to show the place and arrangement of my improved means in the loom. In this view I have shown a few warp threads on their way through the loom parts, to the woven product;

Fig. 2 is a detail view to show relative positions of a pile warp thread and loom parts to help form a loop;

Fig. 3 is a view looking from line 3—3 to Fig. 2;

Figs. 4 and 5 are views similar to Fig. 3 but with the pile thread in different positions in the loop forming operation;

Fig. 6 is a view similar to Fig. 2 but with the parts in still different positions;

Fig. 7 is a vertical plan of a guard frame construction for guiding pile warp threads in the loop-forming operations but with many parts of this construction cut away, to avoid showing too much duplication of identical parts;

Figs. 8 and 9 are detail views showing identical parts of Fig. 7 in side elevation but in different positions with relation to other parts not shown in Fig. 7, all of which are involved in the desired looping manipulation of a pile warp thread, the latter and its positions being also shown in these detail views;

Fig. 10 is a rear view of one of the duplicated elements that are shown mounted in the assembly of Fig. 7;

Figs. 11 and 12 are side and top views of an assembly to serve as pile wires in the loom;

Fig. 13 shows the pile wire of Fig. 11 with an adjusting piece added to make a deeper pile on the fabric;

Fig. 14 is a perspective view of the adjusting piece or insert for the wire of Fig. 13;

Figs. 15 and 16 are views of parts used in the assembly of one type of pile wire;

Fig. 17 shows a different type of adjusting piece;

Fig. 18 illustrates how the pile wire is adjusted by inserting the part of Fig. 17;

Fig. 19 shows a part of the body of a different pile wire;

Figs. 20 and 21 are side and top views of part of a pile wire which is added to the head part of Fig. 19 to form the finger portion of the pile wire;

Fig. 22 is a perspective view of an adjusting piece to be used to increase the size of the loops formed on the pile wire;

Fig. 23 shows a pile wire formed by using the parts of Figs. 19, 20, and 22;

Fig. 24 shows the position of the circular cutter used to cut the loops of the pile warp threads;

Fig. 25 is a view taken on line 25—25 of Fig. 23, showing how the tip of the wire may be bent to insure correct cooperation of the wire with the guard;

Fig. 26 is a modified form of the part of Fig. 25;

Fig. 27 is a view on line 27—27 of Fig. 24 showing the shape of the tip of the wire;

Fig. 28 is a modified form of the part of Fig. 27;

Fig. 29 is a diagrammatic view to indicate how another type of looping is obtained; and

Fig. 30 indicates the mechanism used to reciprocate the grate frame of Fig. 7.

The general plan for weaving pile carpet, and in using my invention, can be seen from Fig. 1. The warp cords or threads, indicated by 1, 2, 7, and 8, are raised and lowered. The weft thread 17 is passed transversely in front of the beater 6. The pile warp threads are looped around flattened pile wires such as 13. The loops are cut by circular knives such as 19. And woven pile fabric is taken up by spiked wheel 18, at the front of the machine.

One of the principal features of my invention is the means and mode of operation for looping the pile warp threads on the pile wires 13. Take the thread 7 as an example and follow it through the parts of Fig. 1. This thread is raised and lowered by the eye 9 in lifting cord 11 weighted by weight 15 at the bottom, the cord 11 being controlled by usual loom means such as the jacquard mechanism. When thread 7 is wanted to form loops it is raised to the position of Fig. 55

1. If it is not wanted to form loops it is lowered in the position corresponding to thread 8, where it will simply run into the ground warp of the carpet. From the elevated position of Fig. 1,
- 5 the thread 7 passes between sheet metal bars of a vertical grate held in frame 26. The thread slants downwardly and gradually passes across the side of the flattened pile wire 13 and ties into the body of the carpet at a weft thread as indicated. The pile wire 13, in the form shown, has a portion riding on the carpet under and back of circular knife 19 for a short distance
- 10 and then a suspended portion extending with a long upwardly slanting sweep so that a free end of the wire is located between sheet metal bars in the grate of frame 26.
- 15

With the parts arranged generally as in Fig. 1, the frame 26 is reciprocated vertically. In this movement cams on the sides of the sheet metal grate bars 21 adjacent thread 7, cam the cord first to the right and then to the left of pile wire 13. The eye 9 is also raised and lowered to move thread 7 first above and then below pile wire 13. The combination of these movements acts to wind the thread in loops upon the wire. These looping operations will be further explained in connection with the detail views. It is enough at this point to understand the result of the intended operations. This result is the looping of the thread 7 on pile wire 13 as such thread moves through the grate bar in the weaving operation.

It will be understood without specific illustration that the grate bar frame 26 extends transversely of the loom over the desired width for the woven product. The grate bars 21, which will be further explained in detail, are closely packed in the frame and make a vertical comb-like arrangement (a part of which is seen in Fig. 7) through which the warp threads or cords pass. There is a flattened pile wire 13 for each adjacent pair of grate bars and a rotary loop cutting knife 19 for each pile wire 13 arranged in a series transversely of the loom.

45 Back of the grate bar frame 26 there are the usual series of eyes 3 and 4 to manipulate the ground warp cords by heddles 5 to time the separation of the warp for the passage of the weft cords.

50 I have merely indicated, by eyes 9 and 10 and the vertical connections 11 and 12 with weights 15 and 16, the usual type of jacquard manipulating means for the pile warp threads. It will be understood that my loom is arranged to carry any desired arrangement of pile warp threads for pattern and color weaving, by duplicating eyes 9 and 10 in staggered and transverse relation across the loom and connecting them to the usual pattern lifting mechanism to place the desired pile threads in position for loop forming purposes. For example, a set of eyes like 9 may be arranged for alignment with each pair of grate bars. Each such eye may carry one or more pile threads all of one or of different colors, or each eye may carry only one thread. The variety of arrangement and manipulation of pile threads for pattern making purposes in weaving is so well known that I hardly need to illustrate the subject beyond mentioning that 60 my loom arrangement is intended to include all these customary parts which I have not shown in the drawings. In my case I use the usual jacquard pattern making mechanism not only to make the pattern but also to move the loop making threads such as 7 in proper timed rela-

tion to the vertical reciprocable movements of frame 26. I will later describe the means for giving the latter movements in connection with a detail view.

5 As will be clear in Fig. 1, each loop made on pile wire 13 is caught by a weft cord 17 and beaten up to position by beater bar 6. The latter operates in the customary manner and needs no description.

10 With the foregoing outline of the assembly and operation of weaving parts shown in Fig. 1, pointed out in a general way, I will now describe in much more detail the preferred form of devices and their operation in the use of my invention.

15 Referring now to Figs. 2 to 6, I will explain in detail the operations involved in the making of the loops in the pile warp threads. At the start of the loop the thread 7 is lifted by the jacquard mechanism and passes upwardly to the left of pile wire 13, being in a position indicated by a in Figs. 2 and 3, the thread being parallel to the flat side of the wire 13. The thread 7 then passes over the wire 13 to the position b of Fig. 4, and then down to the dotted position c. When 20 the thread 7 is next moved to position e of Figs. 4 and 5, a shot of weft 17 is thrown through and the beater 6 moves to the dotted position (see Fig. 6) and returns, forming a tight loop around the wire 13, two of such loops being 25 shown at the right in Fig. 6. The thread 7 then returns to its original position a of Fig. 2. It will be understood that for the sake of simplicity in explanation the ground warp threads and remainder of the pile warp threads are not shown 30 in these views. It should be understood that in the above loop forming operations, the thread 7 is elevated and lowered first above and then below the end of pile wire 13 by the jacquard mechanism and the thread is moved over and under the wire by movement of the frame 26 vertically.

35 Referring to Figs. 7 to 10, I will explain the operation of the grate 5—A held in frame 26 of Fig. 1 in conjunction with the wire 13. The 40 grate 5—A consists of a series of grate-bars 21 fastened to the frame 26 by means of bolts 27 which secure the bars 28 passing through eyes 29 (see Fig. 1) of the grate-bars 21.

45 Each grate-bar 21 consists of two thin metal strips 30 and 31 which are overlapped and secured together, forming the shoulders 32 and 33 (see Fig. 7). To these strips 30 and 31 is riveted a one-piece guard member 33—A forming the shields 34 and 35. The rivets 36 serve as 50 spacers between successive grate-bars 21 in the grate 5—A.

55 The guard member 33—A consists of a piece of sheet metal of the same gauge and of the same width as strips 32 and 33 for part of its length. Near the middle, the strip of the guard member is widened out to nearly double width and a notch 37 cut, see Figs. 8 and 9. The metal is then sprung laterally in each direction from the axis of the metal strip, forming the shields 34 and 35. In assembling the guard member 33—A with the strips 30 and 31, it is slipped over the two strips so that the guards 34 and 35 lie symmetrically about the two strips 30 and 31.

60 When the grate-bars 21 are assembled to form the grate, the guards 34 and 35 overlap on successive grate-bars, see Fig. 7. All the grate-bars are raised and lowered by means to be described for moving frame 26. The pile wire 13 lies between the guard 35 and strip 30 of one grate- 65

bar during part of the time and the guard 34 and strip 31 of an adjacent grate-bar during the rest of the operation, these positions being indicated by 13a and 13b of Fig. 7 the positions being dotted. The pile wire 13 itself does not move but the grate reciprocates vertically as stated.

Referring again to Figs. 2 to 6, I will refer to the operations indicated in those figures and to the ones indicated in Figs. 7 to 9 to show their relation. The grate 5—A is in its lowest position and the wire 13 is in the upper guard 35 at the start of the loop, see Fig. 8. A thread 7 between grate-bars is lifted by the jacquard lifting board and as it rises, passes over the edge 42 of the guard 35, which edge moves the thread laterally so that when it reaches its upper position a it is parallel to the wire 13, see Fig. 8. This position corresponds to a in Figs. 2 and 3. The grate 5—A then moves to its upper position and the wire 13 then occupies the lower guard 34, the position being indicated by 13b of Fig. 7. At the same time that the wire 13 changes relative position the thread 7 follows the path indicated by the arrow 43 in Fig. 7. The thread 7 now lies on the other side of the wire 13 in the position indicated by b of Fig. 4. The jacquard lifting board releases the tension and the thread 7 is pulled downwardly by the lingo-weight 15 (see Fig. 1) until it has reached the position f of Fig. 9 which is the same as c in Fig. 4.

The grate then descends and the wire occupies its original relative position in guard 35, see 13a of Fig. 7. At the same time the thread retraces the path indicated by the arrow 43, so that it is now on the same side that it started on, the position being that shown by e of Figs. 5 and 6. The weft 17 is shot through and the loop beat up tight as shown in Fig. 6. The thread 7 then is ready to move to its upper position a. In these movements the thread is moved up by the jacquard means, over by the cam surfaces of the grate, down by the jacquard, and under by the cam surfaces.

When the thread is passing from one side of the wire to the other, the shoulders 32 and 33 (see Fig. 7) serve to guide the thread and start it on the edges of the guards 34 and 35. The loop cycle and operating means with respect to one thread 7 is the same for all and the desired pattern is made by selecting the right threads 7 for that purpose by the jacquard operation.

I will now describe some of the details of the preferred forms of pile wires.

The wires 13 used in forming the loops 14 are of a novel construction and require only the use of suitable inserts to change their size for different depth rug piles. Referring to Figs. 11 and 12, the wire 13 consists of two thin metal sections 50 and 51 soldered together at 52 with a separator 53 a short distance back of the joining of the two sections. Section 50 is considerably longer than 51 and forms the finger 49 of the wire 13. Another separator 54, Fig. 15, is inserted at the rear of the wire between 50 and 51, the three parts being held together by clip 44, see Fig. 16. This separator 54 has a semi-circular notch 55 of larger diameter than a similar notch 56 in end parts 50 and 51. These end parts are enlarged to about the same shape as separator 54 of Fig. 15. This is indicated in Fig. 11. When the parts are assembled there is a circular trough provided between these end parts of 50 and 51 in which the cutter 19 runs (see Fig. 24). The semi-circle 55 of part 54 forms the bottom of the trough.

A sheet metal insert 57, Fig. 14, may be provided to increase the size of the wire. This metal insert 57 has parallel sides forming an eye 58 and one side 59 extends beyond the joining and forms a tongue 60. When the insert is slipped over the end of the wire 13 the finger 49 of the wire passes through the eye 58, as indicated in the dotted position of Fig. 13. The end of the insert fits into the slot 61 of the wire 13 and the tongue 60 drops into the slot between the separator 53 and the junction 45 of 50 and 51, see Fig. 13.

It may be preferable to use an insert of the type indicated by 62 in Fig. 17, where the thickness is added to the bottom rather than the top 15 of the wire. In using this insert, the separator 54 is not used as the insert 62 is a single piece of metal and forms the separator. Shoulders 63 and 64 cooperate with separator 53 when the insert is in use, the parts being secured by the clip 44 as 20 in the previous assemblies.

In Figs. 19 to 23 is indicated still another type of wire. The body 65 is similar in shape to 54 of Fig. 15, the width however being equal to that of the wire 13 previously described, and all one 25 piece. In addition to the slot 61 is provided a slot 66 slightly longer and more forward on the wire. An insert 67, as indicated by Figs. 20 and 21, is made to cooperate with the slot 61 to form a wire 68 similar to wire 13 but with a T-shaped 30 end 69. An insert 70 having an eye 71 to take 65 and cooperate with slot 66, has a tongue 72 which will just fit into the space 73 of 61, giving an assembly as indicated in Fig. 23.

As indicated in Fig. 25, the tip 69 of wire 68 is 35 given a slight twist 74 which helps to guide the wire as the grate reciprocates. In some types of weaving it may be preferable to put a double twist on the end as indicated by 75 in Fig. 26. In Figs. 27 and 28 are shown a single twist 76 and 40 double twist 77 as applied to a wire having a straight tip.

Referring to Fig. 24, the loops of thread 14 are cut as they come in contact with the rotating wheel 19. This cutter 19 is of very thin metal 45 and rotates between parts 50 and 51 in the trough formed by the circular cuts 55 and 56. Spacing washers 78 are provided between successive cutters along the shaft 79 which is geared to the bottom shaft of the loom. 50

In operation the wires 13 are resting on the top of the fabric and are prevented from moving forward as the carpet is reeled forward by spiked roller 18 (see Fig. 1). A T-iron 80 has bolted to it a rectangular member 81 which fits loosely 55 in slot 82 of wire 13. The iron 80 is in turn bolted to bar 83 which is secured to each side of the loom. The wires, being secured loosely, can be arranged for any spacing of grate-bars 21 for different types of weaves. 60

The grate 5—A may be operated in any of several manners, one of which is indicated in Fig. 30 where an eye 84 is bolted to the frame 26 and connected by the chain 85 to the sprocket 86. This sprocket is keyed to shaft 86' which is 65 rotated by lever 87. A cam 88 on bottom shaft 89 transmits motion to roller 90 of lever arm 91. Lever arm 91 rotates in shaft 92 which passes from one side of the loom to the other, and adjustable rod 93 transmits this motion to lever 70 87. The position of the rod 93 is indicated in Fig. 1. I plan to have several such operating means as shown in Fig. 30 spaced across the loom to take care of the weight of frame 26.

In weaving tapestry and the like, instead of a 75

continuous loop being formed around the wire the thread is passed over the wire and down, the weft shot through and the fabric beaten up. The cord is then returned up the same side it 5 came down and across the wire in the opposite direction and down. The weft is again shot through, the fabric beaten, and the operation repeated. Such a weave is indicated in Fig. 29.

Recalling the description given as to the opera-

10 tion of the grate 5—A in making straight loops, every time the grate 5—A changes from its upper to its lower position the thread 7 crosses either below or beneath the wire; on the upstroke of the grate 5—A the thread 7 goes from left to 15 right and vice versa. In the normal operation the grate 5—A moves upward when the thread 7 is at its highest position and downward when the thread 7 is at its lowest position. By timing the movement of the grate 5—A so that it 20 moves only when the thread is at its highest position, the thread will merely move back and forth across the wire. In this manner the thread will be "hooked" under the weft and back over the wire again as is desired for the tapestry 25 weave.

The advantages of my improvements above disclosed will be clear to one skilled in the art of weaving pile fabric. A particular advantage which appeals to me is in the means for guarding 30 the ends of the pile wires which are suspended between the grate-bars and manipulating the pile threads to form the loops by the vertical movement of the grate-bars so as to give individual manipulation to each thread as 35 it is wound on the wire. There is by this means much less possibility of error in the movement of the threads to the right positions and much less chance of threads breaking. Further advantages are found in the details and convenience of the structural parts.

40 What I claim is:

1. In a loom construction, a vertically reciprocable device having closely spaced vertically arranged guide bars in the form of a grate, a 45 series of pile wires on which loops are formed, said wires having free ends extending between the bars of said grate, pockets having cam surfaces along their sides and located on opposite sides of said bars, said pockets adapted to receive the free ends of the wires so that as the grate is reciprocated vertically the ends of the wires are located first in a pocket on one bar and then in a pocket on the opposite side of an adjacent bar.

50 2. In a loom construction, pile wires over which loops are formed with pile warp threads, each of said pile wires having one end resting on the woven fabric of the loom and the other

end freely suspended between bars of a thread-guiding device, in combination with a vertically reciprocable thread guiding device having a series of closely spaced vertical guard bars with means to constantly contact each pile warp 5 thread adjacent its pile wire and cam surfaces on said guard bars, operable independently of the pile wires to shift the threads transversely of the pile wires.

3. In a loom construction a pile thread guiding device in the form of a vertical grating having composite guide and cam bars therein, each bar comprising a center portion running from top to bottom of the grating and oppositely disposed offset portions along the sides of the center portion to act as cam guides for the threads, one for the upper part of the grating and one for the lower part, the upper and lower cam guide portions of adjacent bars being arranged in slightly overlapped relation with a transverse 20 space between them whereby a vertical reciprocation of the grating may cause each pile thread to be guided first by the cam portion of one bar and then the cam portion of an adjacent bar for lateral shifting of the thread and the center 25 portion of each bar may contact a pile wire to hold it in position for the guided pile thread to make loops thereon.

4. In a loom construction a series of flattened pile wires on which loops are made in the weaving operation, said wires being located in the loom so that their ends extend in freely suspended position rearwardly and a vertically reciprocable guard frame for the ends of said wires, said frame having flattened guard plates 35 vertically arranged adjacent each wire and adapted to guide the thread at one side of each wire in the loop forming operation, the guard plates being extended and bent laterally to cover the ends of the wire so that the thread does not 40 contact the end of said wire during the loop forming operation.

5. In a loom construction a series of pile wires, said wires being located in the loom so their ends extend in freely suspended position rearwardly 45 and a vertically reciprocable guard frame into which the ends of said wires extend, said frame having guard plates vertically arranged on each side of each wire and adapted to independently guide the threads at the sides of the wire without deflecting the wire or allowing the thread to contact the tip of said wire in the operations of forming the loops thereon in weaving and of taking out the loops when it is desirable to reverse the loop forming movements to correct a 50 defect in the weave before continuing the normal operation of the loom.

JOHN LOWRIE.
